US0D1091051S

(12) **United States Design Patent** (10) **Patent No.:** **US D1,091,051 S**
Wen (45) **Date of Patent:** **** Aug. 26, 2025**

(54) **SAFE BOX**

(71) Applicant: **Ningbo Haitu Import and Export Co., Ltd.**, Zhejiang (CN)

(72) Inventor: **Zhengqiang Wen**, Zhejiang (CN)

(73) Assignee: **Ningbo Haitu Import and Export Co., Ltd.**, Zhejiang (CN)

(**) Term: **15 Years**

(21) Appl. No.: **29/974,081**

(22) Filed: **Nov. 20, 2024**

(51) LOC (15) Cl. **99-00**

(52) U.S. Cl. **D99/28**
USPC ....

(57) **CLAIM**

The ornamental design for a safe box as shown and described.

DESCRIPTION

FIG. 1 is a front, right and top perspective view of a safe box, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right and top perspective view thereof, shown in a used condition attached to a magnetic vent cover shown in broken lines; and,

FIG. 10 is an enlarged portion view of encircled portion labeled, "10," in FIG. 1.

The dashed broken lines depict portions of the safe box that form no part of the claimed design. The dashed broken lines in FIG. 9 showing a magnetic vent cover are for the purposes of illustrating environment and forms no part of the claimed design. The dot-dash broken lines in FIGS. 1 and 10 depict the boundaries of the enlarged views and form no part of the claimed design.

1 Claim, 10 Drawing Sheets
